ARTIFICIAL TOOTH AND ANCHOR
THEREFOR

John Breyer, Brooklyn, N. Y.

Application February 16, 1945, Serial No. 578,248

3 Claims. (Cl. 32—9)

This invention relates to improvements in artificial teeth and anchors therefor.

This is a re-filed application of my previous application, Serial Number 454,023, filed August 7, 1942.

The object of the invention is to combine the essential features of two types of teeth at present in use and known as the tube and pontic tooth. The invention provides a unique and substantial backing and anchorage for a tooth, is barely visible and requires little departure from the present way of constructing bridges or appliances.

Another object of the invention is to provide a tooth having the maximum porcelain tooth body for any requirement of an individual grinding without sacrificing the strength of the tooth and backing; and, at the same time, provides a simple and effective structure which can be inexpensively manufactured by modern machinery.

With the above and other objects in view, the invention consists of certain novel details of construction and combination of parts hereinafter fully described and claimed, it being understood that various modifications may be resorted to within the scope of the appended claims without departing from the spirit or sacrificing any of the advantages of the invention.

In the accompanying drawing forming a part of this specification:

Fig. 1 is a rear elevation of a tooth having an anchor construction in accordance with the invention.

Fig. 2 is a side elevation of the tooth and anchor shown in Fig. 1.

Fig. 3 is a vertical sectional view of the tooth and anchor taken on the line 3—3 of Fig. 1.

Fig. 4 is a perspective view of the anchor.

Fig. 5 is a top plan view of the anchor as shown in Fig. 3.

Fig. 6 is a plan view of a plate showing the anchors as an integral part thereof, with the teeth attached.

Fig. 7 is a side view of a plate, partly broken away, showing the bi-cuspid replacement therein.

Referring now to the drawing, in which like characters of reference designate similar parts in the various views, the anchor comprises a standard or backing in the form of a blunt Y, the upper portion or fork 10 of the standard or backing being curved and adapted to occupy a shallow groove formed in the cervical lingual area of a tooth 11, the groove terminating behind the proximal contact of the tooth. The lower member or stem 13 of the standard or backing is curved

transversely and lies in full contact with the tooth within an extension 14 of the groove 12.

A curved anchor pin 15 is fixed in the center of the upper member of fork 10 of the standard or backing and extends into the tooth, see Fig. 3.

Both prongs of the upper Y or fork 10 have the same degree of curvature on top and bottom edges as that of the post, as clearly shown in Fig. 2 of the drawing.

10 The curvature of the post or anchor pin 15 in combination with the curvature of the prongs 10 and the stem 13 absorbs the stress of the tooth from every direction.

The present pin or post anchorages for artificial teeth are straight and vertical and have metal base beneath.

The slight curved motion principle of the pin 15 does not require such base to bear against tissue in the tooth area. Care has to be taken to

20 have post and upper backing member correspond to the same degree of curvature and have the recess in tooth body of sufficient depth and width to receive a backing strong enough to withstand the lateral and vertical masticating stress.

25 It is important that the groove in the tooth be of such character as to receive a standard or backing strong enough to carry and absorb the masticating stress without breakage, especially so if the tooth is to be used on a bridge where

30 the units are connected on the upper portion or fork of the standard or backing. The groove has more width than the depth for the standard or backing so that stress transferred to the standard or backing will be met at a point offering

35 the most resistance; that is, the vertical access of the standard or backing.

In Fig. 6 the plate 16 is formed integral with the stem 13 of the anchor. In Fig. 7 I have shown two bicuspid teeth 17 replaced in the plate.

40 I claim:

1. An anchor for an artificial tooth, comprising a standard or backing in the form of a Y, the upper portion or fork of the standard or backing being curved and adapted to occupy a groove

45 formed in the cervical margin of the tooth of less depth than the width of said upper portion and terminating behind the proximal contact of the tooth, the lower member or stem of the standard or backing being curved transversely and adapted to lie in an extension of the groove in full contact with the tooth, and a curved anchoring pin fixed in the center of the upper member or fork of the standard or backing adapted to 50 extend into the tooth and having the same degree

of curvature on the top and bottom edges as that of the groove.

2. In a tooth anchor, an approximately Y-shaped body having a pair of diverging prongs and a stem extending longitudinally from the juncture of the prongs, the said prongs having an arcuate transverse curvature and a longitudinal curvature in a direction opposed to that of the stem, and an anchoring pin projecting from the medial, inner crotch portion of the body having a longitudinal curvature substantially corresponding to that of the prongs.

3. An anchor for artificial teeth, comprising an

approximately Y-shaped body having a pair of diverging prongs and a stem extending longitudinally from the juncture of the prongs, the said prongs having an arcuate transverse curvature and a longitudinal curvature in a direction opposed to that of the stem so as to fit a groove in the cervical margin of a tooth, and an anchoring pin projecting from the medial inner crotch portion of the prongs having a longitudinal curvature substantially corresponding to the longitudinal curvature of the prongs adapted to extend into the tooth.

JOHN BREYER.
